UNITED STATES PATENT OFFICE.

HENRY N. GORES, OF ST. LOUIS, MISSOURI, ASSIGNEE TO AMERICAN PAPER PRODUCTS COMPANY, OF ST. LOUIS, MISSOURI, A CORPORATION.

SCORING AND SLITTING MECHANISM.

1,129,481.

Specification of Letters Patent. Patented Feb. 23, 1915.

Application filed January 12, 1914. Serial No. 311,390.

To all whom it may concern:

Be it known that I, HENRY N. GORES, a citizen of the United States of America, and a resident of the city of St. Louis and State of Missouri, have invented certain new and useful Improvements in Scoring and Slitting Mechanisms, of which the following is a full, clear, and exact description, reference being had to the accompanying drawings, 10 forming a part of this specification.

My invention relates to a combined scoring and slitting mechanism intended particularly for use in the manufacture of blanks for the production of paper boxes, having 15 flaps foldable into positions to serve as closures for the boxes made from the blanks.

In the manufacture of blanks of the kind herein mentioned, it is common practice to score or crease the paper of the blanks, in 20 order that the paper may be readily bent to produce box walls, and it has also been common practice to notch the paper at the ends of the score lines to produce the closure flaps. As a result of the notching of the paper from 25 which the box blank is produced, the closure flaps are made of less width than the box body sections and, as a consequence, the flaps do not contact at their edges with the adjacent body wall sections to brace the latter, 30 as it is highly desirable they should, to form a strong and durable box.

My invention has for its object to provide a scoring and slitting mechanism by which the paper or paper board, for example, corrugated paper board from which box blanks are produced, may be scored or creased and slit at the ends of the score or crease lines in successive operations, without cutting away the paper between the flaps, so that the latter will be produced in widths corresponding 40 approximately to the widths of the body wall sections. By producing the closure flaps in this manner, the scoring or creasing and slitting is performed expeditiously and 45 with exact uniformity; and the edges of the flaps, when the flaps are folded, occupy such positions relative to the box body wall sections as to bear firmly against the sections to serve as braces for said sections, with obvious resultant strengthening of the box structure.

My mechanism includes wheels for scoring or creasing a sheet of paper, one of said wheels having combined therewith a slitting member adapted to cooperate with the other

wheel to slit the scored paper in lines offset from the score lines. One of the advantages of a device of this kind is the saving effected by utilizing one scoring wheel as a carrier for a slitting member and utilizing the other scoring wheel as another element of the slitting means.

Figure I is a vertical section illustrating a portion of a scoring and slitting machine embodying the features of my invention. Fig. II is a top or plan view of a box blank provided with scores and slits such as are made by my combined scoring and slitting mechanism. Fig. III is an enlarged vertical section taken approximately on line III-III, Fig. I. Fig. IV is an enlarged vertical section taken approximately on line IV-IV, Fig. III.

In the accompanying drawings: 1 and 2 designate rotatable shafts journaled in side frames 3. Scoring wheels A, splined to the shaft 1, are alined with bed wheels B splined to the shaft 2. These scoring and bed wheels may be adjusted longitudinally of the shafts and, when set to the desired positions, they are secured by set screws 4. Each scoring wheel A comprises a hub and a scoring disk 5 secured thereto, the periphery of said disk 5 being shaped to produce the desired crease or score in the sheet of paper. In the operation of the machine, the scoring and bed wheels are rotated and the box blank C passing between said wheels is provided with scores or creases 6. Slits 7 are also formed in the box by means of segmental cutting blades 8 and 9 carried by the scoring wheels A. These segmental cutting blades extend beyond the periphery of the scoring wheels A so as to overlap and cooperate with the bed wheels B during the slitting operation. Each bed wheel B preferably comprises a metal disk 10 and a wooden disk 11 secured thereto, as seen in Fig. IV, which receives the slitting blades 9.

The box blank C shown in Fig. II is provided with the slits 7 to produce closure flaps 12 which form the ends of the box, and the creases or scores 6 are located at the longitudinal corners of the box.

The slitting blades 9 are adjustably secured to the scoring disks 5 by bolts 13 passing through arcuate slots 14 in the scoring disks, (Fig. III). The slitting blades 9 may be adjusted around the axis of the shaft 1 to provide for the manufacture of boxes of 115

different dimensions, and each scoring disk 5 is preferably provided with a scale 16, for convenience in the adjustment of the slitting blade.

5 The scoring disks 5 and the slitting blades 9 are preferably made of thin sheet material, and these parts are therefore reinforced at the slots 14, by means of brace strips 16 clamped in position by the bolts 13, Fig. III.

10 An important feature of the invention lies in the scoring members having scoring edges adapted to produce corner scores in a paper box blank; combined with the slitting blades adapted to form closure slits parallel with, but out of alinement with, said corner scores. It will be noted that each slitting blade is secured to a scoring wheel, and that the cutting edge of each slitting blade is offset from the peripheral scoring edge of the adjacent scoring wheel. A box blank scored and slitted by my combined scoring and slitting device, is provided with corner scores located out of alinement with the side edges of the closure flaps, and the closure flaps 15 may therefore be so formed as to firmly engage the inner faces of the box walls when the box blank is folded. The box structure is thus reinforced by the inner closure flaps which lie within the box body, each of said inner closure flaps being integrally connected to one of the box walls and very firmly fitted to the inner face of an adjoining wall.

15 I claim:

1. A combined scoring and slitting device 20 provided with a scoring member having a scoring edge, and a slitting blade adjacent to said scoring member, the cutting edge of

said slitting blade being offset from and uniformly parallel with the scoring edge of said scoring member.

2. A combined scoring and slitting device 25 comprising rotatable scoring disks each having a peripheral scoring edge, and segmental cutters secured to said scoring disks and extending beyond the peripheral scoring edges 30 of said disks, said segmental cutters being offset from the scoring edges of said disks.

3. A combined scoring and slitting device 35 provided with scoring wheels having peripheral scoring edges adapted to produce corner 40 scores in a paper box blank, and slitting blades adapted to form closure slits parallel with but out of alinement with said corner scores, each slitting blade being secured to one of said scoring wheels, and the cutting 45 edge of each slitting blade being offset from the peripheral scoring edge of the adjacent scoring wheel.

4. A combined scoring and slitting device 50 provided with scoring wheels having peripheral scoring edges adapted to produce corner 55 scores in a paper box blank, and slitting blades adapted to form closure slits parallel with but out of alinement with said corner scores, each slitting blade being arranged 60 alongside of one of said scoring wheels, and the cutting edge of each slitting blade being offset from the peripheral scoring edge of the adjacent scoring wheel.

H. N. GORES.
